Primary Examiner — Mitchell I. Siegel*(74) Attorney, Agent, or Firm* — Adam R. Stephenson, Ltd.(57) **CLAIM**

The ornamental design for a golf alignment device, as shown and described.

DESCRIPTION

FIG. 1 is a front and top perspective view of an implementation of a golf alignment device;

FIG. 2 is a top view thereof;

FIG. 3 is bottom view thereof;

FIG. 4 is a left-side view thereof;

FIG. 5 is a right-side view thereof;

FIG. 6 is a front view thereof;

FIG. 7 is a rear view thereof;

FIG. 8 is a front and top perspective view of another implementation of a golf alignment device;

FIG. 9 is a top view thereof;

FIG. 10 is bottom view thereof;

FIG. 11 is a left-side view thereof;

FIG. 12 is a right-side view thereof;

FIG. 13 is a front view thereof; and,

FIG. 14 is a rear view thereof.

The broken lines shown on the article forms no part of the claimed design.

1 Claim, 8 Drawing Sheets(56)
